UNITED STATES PATENT OFFICE.

DAVID J. CARTWRIGHT, OF SOUTH BETHLEHEM, PENNSYLVANIA.

STORAGE-BATTERY CONSTRUCTION.

1,220,603.

Specification of Letters Patent. Patented Mar. 27, 1917.

Application filed January 15, 1912. Serial No. 671,193.

To all whom it may concern:

Be it known that I, DAVID J. CARTWRIGHT, a citizen of the United States, residing at South Bethlehem, in the county of Northampton and State of Pennsylvania, have invented new and useful Improvements in Storage-Battery Construction, of which the following is a full, clear, concise, and exact description, reference being had to the accompanying drawing, forming a part of this specification.

My invention relates to improvements in storage batteries.

One of the objects of my invention is to provide improved Planté plates of such proportions as to lessen the vertical growth in a plate of a given capacity. Another object is to provide an improved common terminal lug for the plates of a given polarity. Additional objects will appear from the more detailed description given hereinafter.

In the accompanying drawings I have illustrated a storage battery which embodies the features of improvement of my invention.

Figure 1 is a half elevation and a half sectional view of a pair of battery cells or tanks.

Fig. 2 is a sectional elevation on the line 30 2-2 of Fig. 1.

Fig. 3 is a top plan view.

Fig. 4 is an enlarged section of the terminal post.

The individual Planté plates 1 are preferably supported above the bottom of the tanks on suitable blocks of insulation 2. The plates are considerably greater in width than in height, as will be apparent in Fig. 1. Ordinarily, Planté plates are of greater height than width, and the ribs run vertically. Planté plates tend to grow in a direction longitudinal of the ribs which is vertically. In the plates of the novel proportions which I have illustrated the ribs also run vertically, but the vertical growth is reduced, the capacity of the plate being maintained, however, as the area of the plate may be the same as the area of a rectangular plate of the old form.

In certain classes of service Planté plates grow so much that they have to be trimmed about once a year. I have found that with my improved construction, under similar conditions the plates do not need to be trimmed more than once every three years.

By increasing the width of the plates, and accordingly the width of the jars, I increase the horizontal area of the jars and thereby increase the quantity of acid above the plates. As a result the lowering of the acid level, due to evaporation, is slower with my improved construction than in the old construction. Consequently, it is not necessary to flush the jars as often as with previous storage batteries. Furthermore, with an increased area of the bottom of the jars and a decreased height of the plates, the accumulation and deposit of sediment on the bottom is not as rapid per unit of area. In other words, the accumulation does not rise so rapidly as in previous storage batteries of the same capacity. Plates of the same polarity in a given cell are all provided with a common terminal member 3, which is of improved construction. Each lug is provided with an opening 4 adapted to receive an insulated terminal wire. The outer end of the hole is large enough to receive the insulation, and the inner end thereof is contracted to receive the conductor or wire. The wire is held in place by soldering the same through the opening 5 in the top of the lug, or lead burning may be resorted to. I embed a ring of hard rubber 6 in and around the terminal lugs, a red one being arranged around the positive terminal and a black one around the negative terminal. This hard rubber ring preferably extends above and below the top of the battery tank or receptacle, as illustrated in Fig. 1, and is preferably embedded by having the terminal post cast around it, so that it is flush with the outer surface of the post, as illustrated in detail in Fig. 4. This ring or bushing effectually prevents creepage of the acid of the battery along the lead terminal post to the outside of the cell. A soft rubber bushing 14 may be placed between the post and the top of the tank to act as a cushion for the post and to prevent the acid spilling through, in the event the post should fit loosely within the cover.

Another of my improvements relates to the separating block or spacing block on the side of the battery tanks. Ordinarily, a porcelain separating block is used, a screw being used to hold the block in place. If a screw is used which is too long, the lead lining of the jar will be perforated. Furthermore, the porcelain blocks are easily

broken. My improved separating block 7 is made of wood, the inner end of which has a V-shaped slot. This block is inserted in a hole in the side of the wood tanks, the 5 wedge 8 acting to spread the inner end of said block to lock the same firmly in position.

A further feature of improvement resides in the cover to the tanks. The lead lining 9 is extended outwardly and upwardly, 10 as shown at 10, and the cover 11 is provided with a depending flange 12 to strengthen it. The cover is supported by means of this depending flange, which rests on the shoulder 15 at the top of the lead lining 9. The cover extends laterally somewhat beyond said flange and nearly meets the upwardly extending flange 10, the adjacent faces being preferably beveled. The jar may then be 20 readily sealed by means of a low grade solder, or other suitable material. The cover may be removed by first running a knife around the same to cut the seal, the knife blade passing between the beveled surfaces 25 and being received in an annular chamber adjacent thereto.

A further protecting means is indicated at 13 in the form of a housing or case for the battery plates. The two cells of the 30 battery may be arranged upon a common support, as shown in Fig. 1, or, obviously, they may have individual base portions.

I do not limit myself to the exact details of the construction shown and described, as 35 I am aware that various changes may be made within the scope of the invention.

What I claim as new and desire to secure by Letters Patent of the United States is:

1. In a storage battery, in combination, a 40 casing, a cover therefor, a plate inclosed by said casing and having a post extending through said cover, and a hard rubber band secured around said post and between the post and said cover.

45 2. In a storage battery, in combination, a casing, a cover therefor, a plate inclosed by said casing and having a post extending through said cover, and a hard rubber band

secured around said post and fitting snugly between the post and said cover.

3. In a storage battery, in combination, a receptacle having a lead lining, said lining having an enlarged portion at its upper end whereby a shoulder is formed, a cover for said receptacle, said cover having a flange 55 resting on said shoulder and having its periphery extending adjacent the upper edge of said enlarged portion, the adjacent faces coöperating to provide means whereby the cover may be sealed with said lining, a post 60 projecting through said cover, and a hard rubber bushing firmly embedded between said post and said cover.

4. A storage battery, comprising a receptacle having a lead lining, said lining having an enlarged portion at its upper end, whereby a shoulder is formed, a cover for closing said receptacle, said cover having a reinforcing flange resting on said shoulder and having its periphery extending adjacent the upper edge of said enlarged portion, the adjacent faces being beveled and fitting close together, whereby the joint may be 70 readily sealed.

5. A storage battery, comprising a receptacle having a lead lining, said lining having an enlarged portion at its upper end, whereby a shoulder is formed, a cover for closing said receptacle, said cover having a reinforcing flange resting on said shoulder 75 and having its periphery extending adjacent to the upper edge of said enlarged portion, the adjacent faces being beveled and fitting close together, whereby the joint may be 80 readily sealed, and an annular chamber formed between said flange and the shoulder portion permitting the insertion of a knife in cutting through the seal to remove 85 said cover.

In witness whereof, I have hereunto subscribed my name in the presence of two witnesses.

DAVID J. CARTWRIGHT.
